UNITED STATES PATENT OFFICE.

HARRY C. KING, OF BALTIMORE, MARYLAND.

DESIGN FOR A RULING-PEN.

SPECIFICATION forming part of Design No. 35,025, dated September 3, 1901.

Application filed May 31, 1901. Serial No. 62,674. Term of patent 14 years.

To all whom it may concern:

Be it known that I, HARRY CALVIN KING, a citizen of the United States, residing at and whose post-office address is southwest corner 5 Franklin and Eutaw streets, Baltimore, in the State of Maryland, have invented and produced a new and original Design for Ruling-Pens, of which the following is a specification.

Reference is to be had to the accompanying drawings, forming a part of this specification, in which—

Figure 1 is a front elevation of a pen constructed in accordance with my invention.

Fig. 2 is a rear elevation thereof. Fig. 3 is a sectional view on the lines 3 3 of Fig. 1, and Fig. 4 is a similar view on the lines 4 4 of the same figure.

As shown in the drawings, the leading or 20 material feature of my design consists in a three-pointed ruling-pen having an enlarged body portion, with curved sides and V-shaped

spaces between the points of varying length and width.

The numeral 1 in the drawings designates 25 a stem of concavo-convex form in cross-section, gradually widening, forming an enlarged body portion 2, with outwardly and inwardly curved sides 8 and terminating in three split points 3, 4, and 5.

The V-shaped space 6 between the points 4 and 5 is longer and wider than the corresponding V-shaped space 7 between the points 3 and 4.

Having thus described my invention, what 35 I claim is—

The design for a ruling-pen substantially as herein shown and described.

In testimony whereof I affix my signature in presence of two witnesses.

HARRY C. KING.
